DESIGN FOR A PLUG FOR BATHTUBS, SINKS, AND THE LIKE

Edward Gassman, Brooklyn, N. Y.

Application May 24, 1939, Serial No. 85,172

Term of patent 3½ years

To all whom it may concern:

Be it known that I, Edward Gassman, a citizen of the United States and resident of Brooklyn, in the county of Kings and State of New York, have invented a new, original, and ornamental Design for Plugs for Bathtubs, Sinks, and the like, of which the following is a specification, reference being had to the accompanying drawing, forming a part thereof,

Fig. 1 is a perspective view of a plug for bathtubs, sinks, and the like, showing my new design.

Fig. 2 is a front elevational view of the same.

Fig. 3 is a bottom plan view of the same.

I claim:

The ornamental design for a plug for bathtubs, sinks, and the like, as shown.

EDWARD GASSMAN.
